(57) **CLAIM**

The ornamental design for an acoustic baffle as shown and described.

DESCRIPTION

FIG. 1 is a top perspective view of a first embodiment of an acoustic baffle showing our new, original, and ornamental design;

FIG. 2 is a bottom perspective view of the embodiment of FIG. 1;

FIG. 3 is a front view of the embodiment of FIG. 1;

FIG. 4 is a rear view of the embodiment of FIG. 1;

FIG. 5 is a left side view of the embodiment of FIG. 1;

FIG. 6 is a right side view of the embodiment of FIG. 1;

FIG. 7 is a top view of the embodiment of FIG. 1;

FIG. 8 is a bottom view of the embodiment of FIG. 1;

FIG. 9 is a top perspective view of a second embodiment of an acoustic baffle showing our new, original, and ornamental design;

FIG. 10 is a bottom perspective view of the embodiment of FIG. 9;

FIG. 11 is a front view of the embodiment of FIG. 9;

FIG. 12 is a rear view of the embodiment of FIG. 9;

FIG. 13 is a left side view of the embodiment of FIG. 9;

FIG. 14 is a right side view of the embodiment of FIG. 9;

FIG. 15 is a top view of the embodiment of FIG. 9;

FIG. 16 is a bottom view of the embodiment of FIG. 9;

FIG. 17 is a top perspective view of a third embodiment of an acoustic baffle showing our new, original, and ornamental design;

FIG. 18 is a bottom perspective view of the embodiment of FIG. 17;

FIG. 19 is a front view of the embodiment of FIG. 17;

FIG. 20 is a rear view of the embodiment of FIG. 17;

FIG. 21 is a left side view of the embodiment of FIG. 17;

FIG. 22 is a right side view of the embodiment of FIG. 17;

FIG. 23 is a top view of the embodiment of FIG. 17; and,

FIG. 24 is a bottom view of the embodiment of FIG. 17. The dashed lines illustrate portions of the acoustic baffle that form no part of the claimed design.

(Continued)

The appearance of any portion of the acoustic baffle between the break lines shown forms no part of the claimed design. The broken lines are for the purpose of indicating break lines and form no part of the claimed design.
